UNITED STATES PATENT OFFICE.

JAMES ALEXANDER FLANAGAN; OF TORONTO, ONTARIO, CANADA.

COMBINED PRESSER-FOOT AND WORK-GUIDE FOR SEWING-MACHINES.

1,387,142.

Specification of Letters Patent.

Patented Aug. 9, 1921.

Application filed February 4, 1920, Serial No. 356,203. Renewed June 1, 1921. Serial No. 474,301.

To all whom it may concern:

Be it known that I, JAMES ALEXANDER FLANAGAN, of the city of Toronto, in the county of York and Province of Ontario, 5 Dominion of Canada, have invented certain new and useful Improvements in Combined Presser-Foot and Work-Guides for Sewing-Machines; and I hereby declare the following is a full, clear, and exact description of same.

The object of this invention is to combine with the presser foot of a sewing machine, a laterally and vertically adjustable work guide which will determine the position and 15 direction of the stitching with regard to the edge of the work or to the pattern to be followed, the lateral adjustment enabling the work guide to be employed for a multiplicity of purposes such as edge stitching, seaming, 20 raised seaming, quilting and other like uses, and the vertical adjustment permitting of its use on or in connection with materials of different thicknesses without affecting the action of the presser foot on the work, this 25 object being attained as hereinafter described.

In the drawings:

Figure 1, is a perspective view of the work guide combined with a presser foot,
30 Fig. 2, is a perspective view of the presser foot shown in Fig. 1, with the work guide omitted,

Fig. 3, is a detail view of the work guide,
Fig. 4, is a vertical section through the 35 presser foot and vertical member, and

Fig. 5, is a vertical section through the horizontal arm of the work guide.

Like characters of reference refer to like parts throughout the specification and drawings.

The presser foot *a* is formed or provided with a vertical arm or member *b* terminating at its upper end in a tubular socket *c* to receive the lifter bar *d* to which it is secured, preferably by a set screw *e*.

In the arm or member *b* is a recess *f* transverse to the feed of the work having a direction lengthwise of the presser foot. In the presser foot at the base of the recessed face 50 of the arm or member *b* is a groove *g*, the length of which is parallel with that of the recess *f*.

Above the recess *f*, preferably at the junction of the tubular socket with the arm or 55 member *b* is a shoulder *h*, in line with the groove *g*, and engaging the recessed face of

this arm or member is a clamping piece *i*, the upper end of which is seated against the shoulder and the lower end of which is seated in the groove. The clamping piece *i* 60 when in contact with the recessed face of the arm or member *b* converts the recess *f* into a slot for the lateral and vertical adjustment of the work guide.

Operating through a clearance pole *b'* in 65 the arm or member *b* and entering a screw threaded hole *i'* in the clamping piece *i* is a clamping screw *j* which binds the clamping piece tightly against the arm or member *b* and against the horizontal arm of the work 70 guide hereinafter described, the clamping screw having a shoulder *j'* bearing against the back of the arm *b* to limit the movement of the screw through the clearance hole *b'*.

The work guide comprises a guide foot *k*, 75 which may be a complementary part of the presser foot *a*, a vertical arm or member *l* extending upwardly from the heel of the guide foot; and a horizontal arm or member *m*, extending laterally from the vertical 80 arm or member *l*, this horizontal arm or member *m*, during the use of the work guide being entered through the slot *f* and having graduations *m'* thereon which indicate the degree of adjustment of the guide foot 85 to or from the presser foot. For clamping and adjusting purposes this horizontal arm or member *m* is thicker than the depth of the slot *f*, to project slightly beyond the recessed face of the arm or member *b*, and engage 90 the clamping piece *i*, and is less in width than the height of the slot *f* for the vertical adjustment of the arm *m* therein.

In one of the vertical walls of the slot, and lengthwise of it are a plurality of horizontal grooves *o*, one above the other, and on the corresponding face of the horizontal arm or member *m* is a lengthwise rib *p*, to enter any selected groove *o*.

For the adjustment of the work guide the 100 clamping screw is "loosened", to release the pressure of the clamping piece from the horizontal arm or member *m*, which may then freely move laterally and vertically in the slot.

For the vertical adjustment of the work guide the horizontal arm or member *m* is positioned to enter the rib *p* in any selected groove *o*, and for the lateral adjustment of the work guide the horizontal arm or member *m* is moved lengthwise through the slot 110 *f*. The clamping screw is then "tightened"

and binding against the horizontal arm or member *m* securely holds or locks the work guide in its laterally and vertically adjusted position, these adjustments bringing the 5 guide foot into the desired relation with the presser foot and work.

The horizontal arm or member *m* is of a sufficient length to provide for a relatively wide range of lateral adjustment of the 10 work guide, the limit of the lateral adjustment in one direction being the contact of the guide foot with the presser foot of which it may then be a complementary part and the limit of the lateral adjustment in 15 the opposite direction being the length of the horizontal arm, the graduations of which indicate the distance of the guide foot from the presser foot. The limits of the vertical adjustment of the work guide 20 are the top and bottom of the slot *f*. The lateral adjustment of the guide foot from the presser foot determines the relative distance of the stitching from the edge of the work or from the other row or rows of 25 stitching, and the vertical adjustment provides for the use of the work guide on or in connection with materials of different thicknesses without disturbing the original pressure of the presser foot on the material. 30 Depending from the sole of the guide foot is a guide rib or element *g* to engage the edge of the work, or to ride on the material and engage and follow the pattern, or the row or rows of previous stitching. 35 To bring this guide rib *g* into, and maintain it in, correct relation with the work it is only necessary to accurately adjust the guide foot laterally and vertically to the material, the lateral adjustment determining 40 the distance of the stitching from the edge of the work or adjacent row or rows of stitching, and the vertical adjustment providing a contact of the guide foot and guide rib, with the material which will not 45 affect the action of the presser foot on the material.

Having thus fully described my inven-

tion, what I claim as new and desire to secure by Letters Patent is:

1. A work guide for a sewing machine 5 comprising a guide foot having a horizontal arm provided with a lengthwise rib, in combination with a presser foot having a vertical member formed with a transverse recess to receive the horizontal arm of the 10 work guide and of a height sufficient for its vertical adjustment, horizontal grooves being formed in the wall of said recess to receive the rib and maintain the vertical adjustment of the work guide.

2. A work guide comprising a guide foot, having a horizontal arm provided with a lengthwise rib, in combination with a presser foot, a vertical member for the presser foot having a recess formed with horizontal grooves transverse to the feed of the work for the horizontal and vertical adjustment of the work guide, and clamping means opposed to the recess to engage the horizontal member and maintain the adjustment.

3. A work guide comprising a guide foot, having a horizontal member provided with a lengthwise rib, in combination with a presser foot, a vertical member for the presser foot having a recess formed with horizontal grooves transverse to the feed of the work for the horizontal and vertical adjustment of the work guide, and clamping means opposed to the recess to engage the horizontal member and maintain the adjustment, said clamping means comprising a plate opposed to the recess having its upper end abutting against a shoulder on the vertical member and its lower end entered in a groove in the presser foot, and a clamping screw for binding the plate against the horizontal member.

Toronto, September 29th, 1919.

JAMES ALEXANDER FLANAGAN.
